Primary Examiner — Khawaja Anwar*Assistant Examiner* — Julice Seung Eun Oum(74) *Attorney, Agent, or Firm* — Invention To Patent Services; Alex Hobson(57) **CLAIM**

The ornamental design for a combined neck trainer, as shown and described.

DESCRIPTION

FIG. 1 is a front view of the combined neck trainer; FIG. 2 is a right side view of the combined neck trainer; FIG. 3 is a rear view of the combined neck trainer; FIG. 4 is a top view of the combined neck trainer; FIG. 5 is a bottom view of the combined neck trainer; FIG. 6 is a right side view of the combined neck trainer in a compressed state; and, FIG. 7 is an exploded assembly view of the combined neck trainer.

The broken lines in the drawings showing the combined neck trainer illustrate the portions that form no part of the claimed design.

1 Claim, 6 Drawing Sheets(56)
